UNITED STATES PATENT OFFICE.

LOYD SCRUGGS, OF ST. LOUIS, MISSOURI, ASSIGNOR TO COPPER CLAD MALLEABLE RANGE COMPANY, OF ST. LOUIS, MISSOURI, A CORPORATION OF NEBRASKA.

DESIGN FOR A COAL-RANGE.

45,158.

Specification for Design.

Patented Jan. 13, 1914.

Application filed October 27, 1913. Serial No. 797,696. Term of patent 14 years.

To all whom it may concern:

Be it known that I, LOYD SCRUGGS, residing at St. Louis, Missouri, have invented a certain new, original, and ornamental Design for a Coal-Range, of which the following is a specification, reference being had to the accompanying drawing, forming part thereof.

The figure of the drawing is a perspective view of my new design for a coal range.

I claim:

The ornamental design for a coal range, as shown.

LOYD SCRUGGS.
